UNITED STATES PATENT OFFICE.

KARL F. KIRKMAN, OF ERIE, PENNSYLVANIA, ASSIGNOR TO AUTOMATIC PRESS FEEDER COMPANY, OF CHICAGO, ILLINOIS, A CORPORATION OF ILLINOIS.

PRINTING-PRESS.

1,007,209.

Specification of Letters Patent. Patented Oct. 31, 1911.

Application filed October 5, 1910. Serial No. 585,496.

To all whom it may concern:

Be it known that I, KARL F. KIRKMAN, a citizen of the United States, residing at Erie, in the county of Erie and State of Pennsylvania, have invented certain new and useful Improvements in Printing-Presses, of which the following is a specification.

My invention relates to printing presses and the object thereof is to provide an adjustable bearer associated with the type bed of the printing press and arranged to be adjustable inwardly and outwardly with respect to the face of the type bed or frame, such bearer being the part of the press on which the collars or so-called sockets of the inking rollers travel or bear.

In the drawings Figure 1 is a side elevation of a Gordon type of press in connection with which I have chosen to illustrate my invention; Fig. 2 a side elevation of one side of the type bed illustrating my adjustable bearer in position; Fig. 3 a central longitudinal section on the line 3—3 of Fig. 2; Figs. 4 and 5 cross sections on the lines 4—4 and 5—5 respectively of Fig. 2; Fig. 6 a section on the line 6—6 of Fig. 4; Fig. 7 an elevation of the bearer proper; and Fig. 8 an elevation of the operating plate associated with the bearer plate.

In the present instance I have illustrated my invention in connection with a Gordon type of printing press which I have provided with my feeding attachment such as is shown and described in my prior application filed on October 1, 1909, Serial No. 520,512. By reason of the provision of the transfer frame shown herein at *a* for the purpose of handling the sheets of paper in feeding the press the usual construction of type bed and the bearers thereof cannot be employed because of interference between such frame and the bearers. For this reason I have devised the present form of bearers and have made the same adjustable, but it will be understood that my invention is not limited to this particular type of press nor to a press provided with my press feeder or any other feeder but is applicable to printing presses in general.

Referring to the present embodiment of my invention the usual type bed 1 is provided on its opposite sides and adjacent the platen 2, with the bearer devices each of which is similarly made and operated. As

shown each bearer consists of a plate (Fig. 7) forming the bearer proper marked 3, having on its forward edge, that is the edge toward the platen, a flange 3^a which forms the bearing surface for the so-called sockets 60 or collars of the inking rollers hereinafter particularly referred to. Each bearer plate has a pin and slot connection with the side of the type bed the same comprising the slots 3^b and the pins or studs 4. The bearer 65 plate is also provided along its length with two sets of flanges 3^c and 3^d with which co-operate the second or operating plate 5, shown by itself in Fig. 8. This second plate also has a pin and slot connection with the 70 type bed through the medium of its slots 5^a and the same studs or pins 4 that co-operate with the bearer plate proper. The forward edge of this second plate has a series of rack teeth 5^b formed adjacent the opening 3^e in 75 the bearer plate. This rack and said opening are so formed as to receive the so-called quoin key used by printers in locking up their chase, the same tool instead of a special tool being used for sake of convenience.

The parts being assembled as illustrated in Fig. 2 for instance and it being desired to adjust the bearer plate the studs or screws 4 are loosened and the quoin key inserted in 85 the opening 3^e and turned in the proper direction accordingly as it is desired to adjust the bearer inwardly or outwardly. Through the operating engagement between the two plates through the medium of the flanges 90 the bearer plate is caused to move inwardly or outwardly accordingly as the operating plate is moved up or down by the key. When the bearer plate has been moved or adjusted to the proper position the studs or screws 95 are tightened. In order to provide for an accurate adjustment of the bearer and the same adjustment on both sides, I provide these plates with graduations which are indicated in Fig. 2 at 6. As hereinbefore 100 stated, the so-called sockets of the inking rollers travel upon these bearers. As shown in Figs. 4 and 6 the inking roller 7 is provided at its ends with collars or sockets 8 bearing upon said bearers and forming 105 treads traveling upon the bearers, there being recesses or reduced portions at 8^a between the sockets proper and the ends of their inking roller, these recesses having no bearing whatever upon the bearers. In 110

the usual construction of inking roller these
5 sockets are reversely arranged as respects
my present construction, that is, these re-
cessed portions are outwardly located in-
stead of being adjacent the very ends of the
10 inking roller proper. I thus utilize the
usual form of said sockets but reverse them
so as to bring their treads in position to co-
operate with the bearers as clearly illustrated
15 in the drawings.

What I claim is:

1. In combination with a type bed of a
15 printing press, bearers thereon each com-
prising a pair of plates slidable upon each
other but movable in directions at right
angles to each other, one of said plates being
20 movable toward and away from the plane
of the type bed; substantially as described.

2. In combination with a type bed of a
25 printing press, bearers thereon each com-
prising a pair of plates slidable upon each
other but movable in directions at right
angles to each other, one of said plates being
30 movable toward and away from the plane
of the type bed, the other of said plates
having a rack for operating pur-
poses; substantially as described.

3. In combination with a type bed of a
35 printing press, bearers thereon each com-
prising a pair of plates slidable upon each
other and movable in directions at right
angles to each other, and having pin and
40 slot connection with, each other, and means
for operating one of the plates; substan-
tially as described.

4. In combination with a type bed of a
45 printing press, bearers thereon each com-
prising a pair of plates slidable upon each
other and movable in directions at right
angles to each other, one of the plates hav-
50 ing flanges and the other thereof having in-
clined edges coöperating with said flanges;
substantially as described.

5. In combination with the type bed of a
55 printing press, an adjustable bearer at each
side thereof comprising a plate forming the
bearer proper and having sliding engage-
ment with the bed, and a second plate co-
60 operating with the first plate and having
sliding engagement with the first plate and
arranged to move the latter inwardly and
outwardly with respect to the face of the

type bed, said plates being movable in di-
rections at right angles to each other; sub-
stantially as described.

55

6. In combination with the type bed of a
65 printing press, an adjustable bearer at each
side thereof comprising a plate forming the
bearer proper and having sliding engage-
ment with the bed, and a second plate slid-
70 ing upon the first plate and longitudinally
movable, said second plate being arranged
to operatively engage and thereby move the
first plate, said plates being movable in di-
rections at right angles to each other; sub-
stantially as described.

7. In combination with the type bed of a
75 printing press, an adjustable bearer at each
side thereof comprising a plate forming the
bearer proper and having sliding engage-
ment with the bed, and a second plate slid-
80 ing upon the first plate and longitudinally
movable, said second plate being arranged to
operatively engage and thereby move the
first plate, said second plate having a rack
85 to receive an operating tool and the first
plate having an opening to receive the same
tool; substantially as described.

8. In combination with the type bed of a
90 printing press, an adjustable bearer at each
side thereof comprising a plate forming the
bearer proper and having sliding engage-
ment with the bed through a pin and
95 slot connection, and a second plate coöperat-
ing with the first plate and arranged to
move the latter inwardly and outwardly
with respect to the face of the type bed, said
second plate having pin and slot connection
90 with the bed through the same pin as the
first plate; substantially as described.

9. In combination with the type bed of a
95 printing press, an adjustable bearer at each
side thereof comprising a plate forming the
bearer proper and having sliding engage-
ment with the bed, said plate having
side flanges, and a second plate coöperating
with said flanges to move the first plate in-
wardly and outwardly with respect to the
face of the type bed; substantially as de-
scribed.

KARL F. KIRKMAN.
